US0D1106202S

(12) **United States Design Patent** (10) Patent No.: **US D1,106,202 S**
(45) Date of Patent: ** Dec. 16, 2025

(54) **ELECTRONIC DEVICE**

(71) Applicant: **Intel Corporation**, Santa Clara, CA (US)

(72) Inventors: **Aleksander Magi**, Portland, OR (US); **Alexander C. Erdman**, Manlius, NY (US)

(73) Assignee: **Intel Corporation**, Santa Clara, CA (US)

(**) Term: **15 Years**

(21) Appl. No.: **29/816,440**

(22) Filed: **Nov. 22, 2021**

(51) LOC (15) Cl. **14-02**

(52) U.S. Cl.

USPC **D14/374**

(58) **Field of Classification Search**

USPC ... D14/126, 127, 129, 132, 134, 203.7, 307, D14/314, 341, 371, 374-382

CPC G06F 1/1601; G06F 1/1605; G06F 1/162; H04N 5/64

(57) **CLAIM**

The ornamental design for an electronic device as shown and described.

DESCRIPTION

FIG. 1 is a front, top, left perspective view of an electronic device.

FIG. 2 is a rear, top, right perspective view of the electronic device of FIG. 1.

FIG. 3 is a front view of the electronic device of FIG. 1.

FIG. 4 is a rear view of the electronic device of FIG. 1.

FIG. 5 is a top view of the electronic device of FIG. 1.

FIG. 6 is a bottom view of the electronic device of FIG. 1.

FIG. 7 is a right side view of the electronic device of FIG. 1; and,

FIG. 8 is a left side view of the electronic device of FIG. 1. The broken lines illustrate portions of the electronic device that form no part of the claimed design.

1 Claim, 8 Drawing Sheets
